COMBINED ASPIRATION AND RESPIRATION APPARATUS

Joseph M. Magrath, P.O. Box 148,
McCook, Nebr. 69001

Filed Aug. 22, 1968, Ser. No. 13,238

Term of patent 14 years

Int. Cl. D24—02

U.S. Cl. D83—1

FIGURE 1 is a top plan view of a combined aspiration and respiration apparatus, showing my new design;

FIGURE 2 is a front elevation thereof;

FIGURE 3 is a rear elevational view of the aspiration and respiration apparatus shown in FIGURE 2;

FIGURE 4 is a bottom plan view of the aspiration and respiration apparatus shown in FIGURE 3;

FIGURE 5 is a right end elevational view of the aspiration and respiration apparatus shown in FIGURE 2; and

FIGURE 6 is a left end elevational view of the aspiration and respiration apparatus shown in FIGURE 2.

I claim:

The ornamental design for a combined aspiration and respiration apparatus, as shown.
